CLAIM

I claim the ornamental design for an automobile rear view mirror assembly with camera system and retractable GPS display, as shown in the attached drawings.

DESCRIPTION

FIG. 1 is a top view of the assembly with the GPS display retracted.

FIG. 2 is a right side view of the assembly with the GPS display retracted.

FIG. 3 is a front view of the assembly with the GPS display retracted.

FIG. 4 is a front perspective view of the assembly with the GPS display retracted.

FIG. 5 is a bottom view of the assembly with the GPS display retracted.

FIG. 6 is a front view of the assembly with the GPS display deployed.

FIG. 7 is a front perspective view of the assembly with the GPS display deployed.

FIG. 8 is a right side view of the assembly with the GPS display deployed; and,

FIG. 9 is a bottom view of the assembly with the GPS display deployed.
